MOTOR DRIVEN TOOTHBRUSH

Francis M. Van Fleet, Washington, D. C.

Application September 13, 1934, Serial No. 743,914

5 Claims. (Cl. 15—22)

This invention relates to certain new and useful improvements in motor driven toothbrushes.

The primary object of the invention is to provide a toothbrush wherein a brush head is caused to travel through a circular or orbital path with the toothbrush restrained from rotary movement and in operative engagement with a portable electric motor of the hand type for imparting movement thereto.

10 A further object of the invention is to provide a motor driven toothbrush of the foregoing character wherein the motor casing and extension thereof housing the motor and operating mechanism of the toothbrush is formed of "Bakelite", hard rubber, or other similar substance with metallic bearings within the casing for the movable elements of the brush operating mechanism for the reduction of wear on the parts.

15 A still further object of the invention is to provide a motor driven toothbrush wherein a disk is rotatably supported in the brush backing with an eccentric pin connection between the disk and a rotatable member and a slotted arm and pin connection between the brush backing and an immovable part of the device for causing the toothbrush to travel in a non-rotative circular or orbital path.

20 With the above and other objects in view that will become apparent as the nature of the invention is better understood, the same consists in the novel construction, combination and arrangement of parts to be hereinafter more clearly described and then claimed.

25 In the accompanying drawing which shows a preferred embodiment of the present invention:

Figure 1 is a bottom plan view of a motor driven toothbrush constructed in accordance with the present invention.

Figure 2 is a side elevational view of the device,

Figure 3 is a longitudinal sectional view taken on line 3—3 of Figure 2,

Figure 4 is a detail sectional view taken on line 4—4 Figure 3,

Figure 5 is a fragmentary longitudinal sectional view of the brush end of the device showing the slotted arm and pin connection between the eccentrically mounted brush head and casing,

Figure 6 is a cross sectional view taken on line 6—6 of Figure 3, showing the worm and worm wheel drive for the brush head, and

Figure 7 is a plan view of the eccentrically mounted disk carrying the stub shaft of the brush head.

The portable hand motor is of usual construction and embodies a casing 10 having a removable side wall 11 to permit access to the mechanism of the electric motor, the shaft of the electric motor being equipped with a knurled starting wheel 12 that projects through a slotted opening in the casing 10 and the cover 11.

One of the novel features of the present invention is to provide a tubular extension 13 at one end of the motor casing 10 that is provided at its outer end with a laterally offset portion 14 for purposes presently to appear, one side of the tubular extension 13 and offset portion 14 comprising a removable section 15 to permit access to the toothbrush operating mechanism inwardly of said removable section. It is intended that the motor casing with the extension 13 and removable section 15 be constructed of "Bakelite" or similar material, and this "Bakelite" casing and extension are lined with metallic bearings for movable parts of the brush operating mechanism.

As shown more clearly in Figure 3, shaft 16 of the motor 17 adjacent the extension 13 is provided with a key end 18 that is received within the key socket 19 of a shaft 20 extending through the casing extension 13. A metallic bearing 21 within the extension 13 receives the key socket 19 and shaft 20, the bearing 21 being suitably anchored within the extension 13.

20 A recess is formed in the adjacent faces of the outer end of the extension 13, the offset portion 14 and the removable section 15 and these recesses are lined with metallic bearings 22 as shown in Figures 3 and 5 for the rotative reception of a stub shaft 23. The inner end of the stub shaft 23 is provided with a key socket 24 to receive the outer key end 25 of the shaft 20. A worm 26 is fixed to the stub shaft 23 at the outer end of the extension 13.

25 As shown in Figures 3, 4, and 6 the shaft 27 is journaled in the top and bottom walls of the offset portion 14 of the extension 13, and has a worm wheel 28 fixed thereto that is in mesh with the worm 26. The shaft 27 extends through the outer end of the extension 13 and as shown in Figures 4 and 7 is eccentrically connected to a disk 29 that is freely mounted within a cup-shaped cap 30 that has its free edge spun inwardly as shown at 31 to overlie the inner face of the disk 29 for retention thereon, the annular wall of the cap 30 being screw-threaded. A brush head 32 is carried by a cup-shaped backing 33 that is internally threaded for threaded engagement with the cap 30 as shown in Figure 4, the brush being removable to permit replacement or the like. A

slotted arm 34 projects laterally of the brush backing 33 and a pin 35 projecting outwardly of the outer end of the tubular extension 13 extends into the slot of the arm 34 for preventing rotary movement of the brush head, but permitting the latter to travel in a circular or orbital path.

The electric motor is adapted to be connected to the source of energy by the usual flexible conductor and rotation is initially imparted to the shaft 16 of the electric motor by the starting wheel 12 that projects through the casing 10. Rotation of the motor shaft 17 is communicated to the worm 26 and worm wheel 28, the latter rotating the shaft 27 and eccentric disk 29 within the cap 30. In view of the eccentric mounting of the brush backing 33 with respect to the shaft 27 and the slotted arm and pin connection 34 and 35 between the brush backing and the outer end of the tubular extension 13, the brush head 32 is caused to travel in a non-rotative circular or orbital path and this action or movement is especially effective for the brushing or cleaning of teeth. It is to be understood that other devices may be engaged with the cap 30, such as devices for massaging the gums or for other purposes.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

35 I claim as my invention:—

1. In a motor driven toothbrush, a handle, a brush head movably mounted at the outer end of the handle, motor-operated means in the handle operatively associated with the brush head for moving the latter in an orbital path, cooperating means including a slotted arm and pin extending into the arm slot respectively carried by the brush head and handle to prevent rotary movement of the brush head, the motor-operated means including a shaft driven by the motor, a worm on the shaft, a stub shaft, a worm wheel on the stub shaft engaged with the worm and an eccentric connection between the stub shaft and brush head.
- 40 2. In a motor driven toothbrush, a handle, a brush head movably mounted at the outer end of the handle, motor-operated means in the handle operatively associated with the brush head for moving the latter in an orbital path, cooperating means including a slotted arm and pin extending into the arm slot respectively carried by the brush head and handle to prevent rotary movement of the brush head, the motor-operated means including a shaft driven by the motor, a worm on the shaft, a stub shaft, a worm wheel on the stub shaft engaged with the worm and an eccentric connection between the stub shaft and brush head.
- 45 3. In a motor driven toothbrush, a handle, a brush head movably mounted at the outer end of the handle, motor-operated means in the handle operatively associated with the brush head for moving the latter in an orbital path, means to prevent rotary movement of the brush head including a slotted arm and pin connection between the brush head and handle, the motor-operated means including a shaft driven by the motor, a worm on the shaft, a stub shaft, a worm wheel on the stub shaft engaged with the worm, a disk to which the stub shaft is eccentrically attached, a cap in which the disk is rotatable, and the brush head being removably attached to the cap.
- 50 4. In a motor driven toothbrush, a handle, a brush head movably mounted at the outer end of the handle, motor-operated means in the handle operatively associated with the brush head for moving the latter in an orbital path, cooperating means carried by the brush head and handle to prevent rotary movement of the brush head, the motor-operated means including a shaft driven by the motor, a worm on the shaft, a stub shaft, a worm wheel on the stub shaft engaged with the worm, a disk to which the stub shaft is eccentrically attached, a cap in which the disk is rotatable, and the brush head being removably attached to the cap.

5. In a motor driven toothbrush, a handle, a brush head movably mounted at the outer end of the handle, motor-operated means in the handle operatively associated with the brush head for moving the latter in an orbital path, the motor-operated means including a shaft driven by the motor, a worm on the shaft, a stub shaft, a worm wheel on the stub shaft engaged with the worm, a disk to which the stub shaft is eccentrically attached, a cap in which the disk is rotatable, the brush head being removably attached to the cap and cooperating means carried by the brush head and handle for restraining the brush head from rotary movement and effecting orbital movement of the brush head.

6. In a motor driven toothbrush, a handle, a brush head movably mounted at the outer end of the handle, motor-operated means in the handle operatively associated with the brush head for moving the latter in an orbital path, means to prevent rotary movement of the brush head including a slotted arm and pin connection between the brush head and handle, the motor-operated means including a shaft driven by the motor, a worm on the shaft, a stub shaft, a worm wheel on the stub shaft engaged with the worm, a disk to which the stub shaft is eccentrically attached, a cap in which the disk is rotatable, and the brush head being removably attached to the cap.

7. In a motor driven toothbrush, a handle, a brush head movably mounted at the outer end of the handle, motor-operated means in the handle operatively associated with the brush head for moving the latter in an orbital path, cooperating means carried by the brush head and handle to prevent rotary movement of the brush head, the motor-operated means including a shaft driven by the motor, a worm on the shaft, a stub shaft, a worm wheel on the stub shaft engaged with the worm, a disk to which the stub shaft is eccentrically attached, a cap in which the disk is rotatable, and the brush head being removably attached to the cap.

8. In a motor driven toothbrush, a handle, a brush head at the outer end of the handle, a motor driven shaft in the handle, a stub shaft, gear connections between the two shafts, a disk eccentrically attached to the stub shaft, said brush head having the disk rotatably mounted therein and cooperating means carried by the brush head and handle for holding the brush head against rotation during eccentric rotation of the disk.

FRANCIS M. VAN FLEET.
